UNITED STATES PATENT OFFICE.

JOHN GYPE AND CHRISTIAN GYPE, OF TEDROW, OHIO.

CIDER-PRESS.

SPECIFICATION forming part of Letters Patent No. 310,272, dated January 6, 1885.

Application filed November 3, 1884. (No model.)

To all whom it may concern:

Be it known that we, JOHN GYPE and CHRISTIAN GYPE, citizens of the United States, residing at Tedrow, in the county of Fulton and State of Ohio, have invented a new and useful Improvement in Cider-Presses, of which the following is a specification, reference being had to the accompanying drawings.

Our invention relates to cider-presses; and it has for its object to provide a device of this character which shall be cheap and simple in its construction, effective in its operation, and one that will be strong and durable.

With the above and other ends in view the invention consists in the improved construction and combinations of parts hereinafter fully described, and pointed out in the claims.

In the drawings, Figure 1 is a plan view of a cider-press constructed in accordance with our invention, and Fig. 2 is a longitudinal vertical section of the same on the line *x x* of Fig. 1.

In the accompanying drawings, in which like letters of reference indicate corresponding parts in both the figures, A represents the supporting-frame, which consists of the longitudinal side beams, B B'. The upper side beams, B, are connected at their ends by means of tie-beams C, while the beams B' are connected at their ends by similar cross or tie beams, D. Upon the under side of the upper side beams, B, near each end thereof, is provided a cross-beam, a, while the lower beams, B', are provided with similar beams, b', arranged on a vertical line with the beams a.

E represents a shaft which has bearing at its upper end in a cross-beam, b, and at its lower end in a cross-beam, c, said beams being located about midway between the ends of the supporting-frame, as shown. Upon the shaft E is rigidly mounted a gear-wheel, F, said wheel being located just below the beam b, while upon said shaft E, just above the beam c, is mounted a pinion-wheel, d. F' represents a shaft which is mounted in boxes secured to the cross or tie beams C and one of the beams a. Upon the inner end of this shaft F is mounted a gear-wheel, G, which is adapted to mesh with the gear-wheel F, said shaft having on its outer end a spur-wheel adapted to receive a chain or belt for driving the shaft F'.

G G' represent shafts which are mounted in the cross or tie beams a b'. Each of these shafts G G' is provided with a gear-wheel, f, which is located between the beams a b', and is adapted to mesh with the pinion-wheel d. The ends of these shafts project upwardly beyond the supporting-frame, and the shafts G G' are provided with screw-threads, the threads upon said shafts being a slight distance above the said supporting-frame, as shown.

H represents a follower-beam having near each end an interiorly screw-threaded seat or bush, g, to receive the screw-threaded ends of the shafts G G'. Upon the under side of the follower-beam H, midway between the ends of the same, is secured a follower or platen, I, the operation of which will be more fully described. Upon the shaft G' is mounted a clutch, the upper section or disk of which is loose on said shaft, while the lower section or disk is fitted with grooves adapted to receive a spline on the said shaft. It will thus be seen that said disks, when in the position shown in Fig. 2, do not turn with the shaft; but as soon as the lower section of the clutch is pushed upwardly, so that the groove engages the spline on the shaft, said disks turn with the shaft. The lower section or disk of the clutch J is raised and lowered by means of a lever, K, which is pivoted as shown. Upon the upper side of the supporting-frame A, on each side of the beam b, are provided cross-beams L, having grooves h. At the end 85 of the frame adjacent to the shaft G' is provided a cross-beam, M, having a groove or channel, m, upon its upper face.

N represents a platform which has an opening about its center. This opening is adapted to receive the upper section of the clutch, and the platform is secured to said section in any suitable manner, so that it will turn therewith. It will be observed that while one end of the platform is directly under the platen or follower, the other or opposite end is located outside of and beyond the supporting-frame. The platform is provided on its under side with ribs or feathers, which fit in the grooves in the platform-supporting beams.

The operation is as follows: A tub containing apples is placed upon the inner end of the platform. Motion is then imparted to the shafts G G' through the gearing before de-

scribed. The shafts in revolving turn in the screw-threaded seats of the follower-beam and lower the same, the platen or follower entering the tub containing the apples or other fruit and expressing the juice therefrom. As soon as the fruit in the tub has been sufficiently pressed the gearing is reversed, thus raising the follower-beam and follower. As soon as the follower has cleared the tub—that is, raised therefrom—the lower section of the clutch is pushed upwardly into engagement with the upper section, thus causing said clutch to become rigid on the shaft, and as the platform is rigidly secured to the upper section of the clutch it is turned, so as to carry the tub outside of the frame, thus bringing another tub under the follower, the latter-mentioned tub having been filled while the other one was being operated upon. As soon as said tub has arrived at the point beneath the follower the sections composing the clutch are thrown from engagement with each other, thus leaving the platform at a standstill. The gearing is again reversed and the operation continued, as above described.

It will be seen that by the construction of press shown and described the tubs containing the apples or other fruit may be readily brought beneath the follower and the juice expressed therefrom.

The press above described is simple, may be manufactured at a slight cost, is effective in its operation, and is strong and durable.

Having fully described our invention, what we claim as new, and desire to secure by Letters Patent, is—

1. The combination, with a suitable supporting-frame, of shafts, screw-threaded at their upper ends, mounted therein, a follower mounted on said shafts, and a platform for supporting the tubs containing the fruit to be operated upon, as set forth.

2. The combination, with a suitable supporting-frame, of shafts, screw-threaded at their upper ends, mounted therein, a follower-

beam carrying a follower or platen, and a platform, substantially as and for the purpose set forth.

3. The combination, with a suitable supporting-frame, of shafts, screw-threaded at their upper ends, mounted therein, means, substantially as described, for operating said shafts, a follower-beam carrying a follower, and a platform, substantially as and for the purpose set forth.

4. In a cider-press, the combination, with the shafts G G', and means, substantially as described for operating the same, of a follower-beam having a follower secured thereto, and a movable platform for supporting the tubs containing the fruit to be operated upon, as set forth.

5. In a cider-press, a movable platform adapted to be turned, substantially as described, when the follower is raised, as set forth.

6. In a cider-press, the combination, with a suitable supporting-frame, of the shafts G G', mounted therein, gearing, substantially as described, for operating said shafts, a follower-beam, a follower, a platform loosely connected with one of said shafts, and a clutch, substantially as set forth.

7. The combination, with a suitable supporting-frame, of shafts G G', mounted therein, gearing, substantially as described, for operating said shafts, a follower-beam mounted on said shafts, a follower secured to said beam, a platform having ribs upon its under side, supporting-beams having grooves to receive the same, and a clutch, substantially as set forth.

In testimony that we claim the foregoing as our own we have hereto affixed our signatures in presence of two witnesses.

JOHN GYPE.
CHRISTIAN GYPE.
